COMBINATION GIRDLE AND HERNIA TRUSS

Julius Rosenzweig, New York, N. Y.

Application January 12, 1943, Serial No. 472,117

14 Claims. (Cl. 128—96)

This invention relates to a combination girdle and hernia truss, and the like articles.

An object of this invention is to provide an article of the character described having pressure pads which are adjustable to fit different people and to place the pad in the necessary position, said pads being also removable to permit cleaning of the girdle, and also to permit the girdle to be used without the pads, as after an operation or by active people to constrict and support the body, and also to permit the covering for the pad to be cleaned.

Another object of this invention is to provide an article of the character described which will loosen somewhat when the wearer sits and tightens when the wearer is active as when he runs, jumps or exercises, thus providing relaxation when it is desired and the necessary support when it is needed most.

Still a further object of this invention is to provide an article of the character described, having padding in the leg bands for comfort, and in which the leg bands are integral parts of the girdle and have free ends which can be laced to the body of the girdle by the girdle laces, thus permitting adjustment of the leg bands to suit the wearer.

Yet a further object of this invention is to provide an article of the character described having eyeletted slit edges which may be laced together to tighten the article on the body, the slit edges being interconnected by gussets forming pockets to receive the ends of the leg bands and the pressure pads, said pads likewise being provided with openings to permit the pads to be laced in place by the laces which tighten up the article on the body and attach the ends of the leg bands to the body of the article.

Yet a further object of this invention is to provide an article of the character described having supporting straps which may either be passed over the shoulders of the wearer or around the body of the wearer and buckled in place to retain the article on the body.

Still another object of this invention is to provide an article of the character described in which the leg bands are formed with pockets to receive padding removably inserted therein, the padding having means to facilitate insertion thereof into said pockets.

Still a further object of this invention is to provide an article of the character described having means to support the testicles when worn by men.

Still another object of this invention is to pro-

vide in an article of the character described a hernia pressure pad which is resilient and highly comfortable to wear.

Yet a further object of this invention is to provide a strong and durable combination girdle and truss of the character described which shall be relatively inexpensive to manufacture, easy to don and doff, comfortable to wear and yet practical, sanitary and efficient in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings in which is shown one of the various possible illustrative embodiments of this invention,

Fig. 1 is a front elevational view of a combination girdle and truss embodying the invention, or a figure;

Fig. 2 is a side elevational view thereof;

Fig. 3 is an enlarged cross-sectional view taken on line 3—3 of Fig. 1;

Fig. 4 is a cross-sectional view taken on line 4—4 of Fig. 3;

Fig. 4a is a perspective view of a modified form of truss pad;

Fig. 5 is a top plan view of the spring used in the truss pad;

Fig. 6 is a cross-sectional view taken on line 6—6 of Fig. 5;

Fig. 7 is a top plan view of the inside of the improved article stretched out flat;

Fig. 8 is an enlarged cross-sectional view taken on line 8—8 of Fig. 7;

Fig. 9 is a top plan view of one of the leg pads;

Fig. 10 is a partial front view of one of the girdle sleeves showing the truss pocket and end of leg band laced to one of the sleeves;

Fig. 11 is a partial, front elevational view of an article embodying the invention and illustrating a modified construction, on a figure;

Fig. 12 is a partial enlarged view of a portion of the article shown in Fig. 11;

Fig. 13 is a front view of a pad illustrating a modified form;

Fig. 14 is a perspective view of the pocket for the pad illustrated in Fig. 13;

Fig. 15 is a view of the ball inserted into the pocket of Fig. 14;

Fig. 16 is a rear view of a modified form of insert for the pocket shown in Fig. 14; and

Fig. 17 is a perspective view of the article shown in Figs. 11 and 12 but with the straps around the body instead of around the shoulders.

Referring now in detail to the drawings, 10 designates a combination girdle and truss shown in the drawing on a figure 11. Said article 10 comprises a pair of similar, symmetrical sections 12 of textile material of generally triangular shape each having an upper edge portion 12a just below the chest, a substantially vertical edge portion 12b at the front of the body, and a downwardly inclined edge portion 12c extending from the side of the body to the crotch. Sections 12 thus cover the abdomen region of the body. Said sections 12 are interconnected at their inner edges 12a by a vertical gusset 13, extending from the upper edge to a point above the crotch, thus terminating short of the lower ends of sections 12.

The outer edges of gusset 13 are turned in and stitched to the inner edges 12a of sections by double seams spaced in parallel relation and the stitched together portions are provided with eyelets 16. The rows of eyelets may be laced together by a lace 17. Gusset 13 thus forms a 20 backing sleeve for the lacing. At the lower ends of sections 12 are strings 19 which may be tied together to provide a support beneath the testicles when the article 10 is worn by a man. If used for a woman, the lower ends of sections 12 may be omitted.

The girdle 10 further comprises a pair of similar, symmetrical sections 20 of textile material, having edges 21 parallel to edges 12c of sections 12 and extending around the sides of the body at the hip and terminating in narrowed leg strap portions 22, each passing around the legs, beneath the buttocks, and forwardly at the crotch. The narrowed portions 22 are folded longitudinally inwardly and the meeting edges 23 are stitched together as at 23 to form a sleeve 24 open at its end nearest the section 20 from which it extends. The end of extension 22 is stitched flat to form a tab 25. Tabs 25 are each provided with two rows of eyelets 26.

The inner edges 20a are connected to edges 12c of sections 20 by gussets 30. The outer edges of gussets 30 are likewise turned in and stitched to edges 12c, 20a by double lines of stitching 14, the stitched together edges being provided with rows of eyelets 32. Thus gussets 30 form backings for the lacing 33 which interconnects eyelets 32, and also form sleeves or pockets to receive the free ends of the leg straps 22, and also to house hernia pressure pads 35 as will be explained hereinafter.

Within the sleeve portion 24 of each leg strap 22 is a padding member 36. Said padding member may comprise a longitudinal bag filled with padding material 38, and having an open pocket 39 at one end so that a stick may be engaged in the pocket to push the padding into sleeve 24. The padding 36 is removable and replaceable, and facilitates washing the article 10.

The lacing 33 may be laced through eyelets 26 in tabs 25 to attach the leg straps in adjusted position to suit the wearer.

Means is provided to strap the upper portions of girdle 10 to the body of the wearer. To this end there is provided a strap 40 stitched at one end 41 to the upper edge of one section 12 and extending around the back of the wearer. The free end of strap 40 may be buckled to a buckle 42 attached to the upper edge of the other section 12.

In addition there is stitched to the upper corner of each section 20 as at 44, a strap 45 extending rearwardly and upwardly around an opposite shoulder of the wearer and then down the front of the wearer, the free end of said strap being attached to a buckle 46 stitched to the upper end of the opposite section 12.

The pressure pad 35 comprises a bag 50 made of a flat piece of cloth or leather 51 and a piece 10 of cloth or leather 52 stitched thereto at three sides leaving one end open. Piece 51 has holes 53 which may be registered with eyelets 26 in the leg straps and eyelets 32 of gussets 30 to be laced together in adjusted position by lacing 33. The pads 35 are thus received in sleeves or gussets 30 and may be laced in any desired adjusted positions in said sleeves.

In each bag 50 is a metal spring 60 shown in Figs. 5 and 6 to be made of a single piece of wire bent into a continuous coil of rectangular convolutions 61, with one side of said convolutions attached together by a sleeve 62 to cause the spring to assume a fan shape with rectangular arms 61 extending in fan shape from said sleeve.

When inserting spring 60 into bag 50, the arms are pressed together and the sleeve end of the spring is pushed in first into the bag. The spring then opens up as much as the bag will permit and causes a resilient pressure against the hernia area of the body.

In Fig. 4a there is shown a hernia pressure pad 65 having a bag 66 made up of two V-shaped side pieces 66 interconnected by a gusset 67. Bag 66 is thus V-shaped. One end of gusset 67 has lace openings 68. In bag 66 is a spring 60 the same as described above.

In Figs. 13, 14 and 15 is shown a hernia pressure pad 70 illustrating a modified construction. Pad 70 comprises a bag 71 having a central opening 72' in which is inserted a small rubber ball 72 such as children play with, or any other suitable padding material. Bag 71 has tabs 73 and 74 at the ends thereof, formed with spaced openings 73a, 74a for receiving the lacing 33.

Tab 74 is furthermore formed with a slot 75 and tab 73 with a neck 76.

Tab 73 may be passed through slot 75, the neck 76 facilitating such operation. The tabs 73, 74 may then be laced to the eyelets 32.

In Fig. 16, there is shown a padding device 80 to replace ball 72. Device 80 is a rubber ball cut almost through in half and then opened up. A flat piece of cardboard or wood 82 is then placed against the flat surfaces of the cut ball and attached thereto by a string 83 tied around the neck between the two substantially hemispherical portions.

In Figs. 11, 12 and 17 there is shown an article 10a similar to article 10 except for the straps which attach the upper portion of the article to the body.

In article 10a, side sections 20 are each provided with a buckle 86 and with a pair of converging strips 87 and 88 stitched together as at 89. Extending from the meeting portion of strips 87, 88 are a pair of straps 90 and 91, the former being shorter than the latter. At the upper end of each section 12 is a buckle 94.

As shown in Fig. 11, each strap 90 on one side is passed around the back of the wearer and attached to buckle 86 at the other side. Each strap 91 passes rearwardly and upwardly over an opposite shoulder and down the front of the wearer and attached to the buckle 94 at said opposite side.

As shown in Fig. 17 the straps 91 may be passed all around the body below the arms, rearwardly and then around the front and attached to the buckle 94 at the same side of article 10a as the stitched end of said strap.

If desired, the free end of strap 90 may be passed through the triangular opening between strips 87, 88 on an opposite side of article 10a.

It will be noted that when the wearer sits the leg straps move up and loosen the girdle, but when the wearer is active the leg straps are moved down and increase the pressure of the pads on the body.

It will be further noted that the girdle or truss is only at the front of the body where it is needed, except for the straps, thus leaving the back of the body free of constriction.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. An article of the character described, comprising a pair of sections, a gusset interconnecting said sections, said gusset and the adjacent edges of said sections being provided with eyelets, lacing for said eyelets and a pressure pad within said gusset.

2. An article of the character described, comprising a pair of sections, a gusset interconnecting said sections, said gusset and the adjacent edges of said sections being provided with eyelets, lacing for said eyelets and a pressure pad within said gusset, said pad having lace openings and said lacing passing through said openings.

3. An article of the character described, comprising a pair of sections, a gusset interconnecting said sections, said gusset and the adjacent edges of said sections being provided with eyelets, lacing for said eyelets and a pressure pad within said gusset, said pad comprising a bag formed with lace openings, a resilient member within said bag, and said lacing passing through said openings.

4. A girdle comprising a pair of front sections, a gusset interconnecting adjacent edges of said front sections, said adjacent edges being formed with eyelets, lacing passing through said eyelets, said sections extending below said gusset, and strings at the lower ends of said sections adapted to be tied together beneath the testicles of the wearer to aid in supporting the same.

5. An article of the character described, comprising front sections, side sections connected to said front sections by gussets, the edges of said front and side sections adjacent said gusset being formed with eyelets, lacing for said eyelets, said side sections terminating in narrowed leg bands, the free ends of said leg bands being formed with lace openings and extending into said gussets and being laced by said lacing.

6. An article of the character described, comprising front sections, side sections connected to said front sections by gussets, the edges of said front and side sections adjacent said gusset being formed with eyelets, lacing for said eyelets,

said side sections terminating in narrowed leg bands, the free ends of said leg bands being formed with lace openings and extending into said gussets and being laced by said lacing, portions of said leg bands being sleeves, and padding within said sleeves.

7. An article of the character described, comprising front sections, side sections connected to said front sections by gussets, the edges of said front and side sections adjacent said gusset being formed with eyelets, lacing for said eyelets, said side sections terminating in narrowed leg bands, the free ends of said leg bands being formed with lace openings and extending into said gussets and being laced by said lacing, and hernia pressure pads within said gussets.

8. An article of the character described, comprising front sections, side sections connected to said front sections by gussets, the edges of said front and side sections adjacent said gusset being formed with eyelets, lacing for said eyelets, said side sections terminating in narrowed leg bands, the free ends of said leg bands being formed with lace openings and extending into said gussets and being laced by said lacing, and hernia pressure pads within said gussets, said pads having lace openings to receive said lacing.

9. An article of the character described, comprising front sections, side sections connected to said front sections by gussets, the edges of said front and side sections adjacent said gusset being formed with eyelets, lacing for said eyelets, said side sections terminating in narrowed leg bands, the free ends of said leg bands being formed with lace openings and extending into said gussets and being laced by said lacing, and hernia pressure pads within said gussets, said pads having lace openings to receive said lacing, portions of said leg bands being sleeves, and padding removably inserted into said sleeves.

10. A combination girdle and hernia truss, comprising a pair of similar, symmetrical front sections, a gusset having its side edges turned in stitched to the adjacent edges of said sections, eyelets carried by the gusset and the edges of said sections stitched thereto, a pair of side sections connected to the outer edges of said front sections by gussets having their side edges turned in and stitched to said front and side sections, lacing for each of said gussets forming sleeves of said gussets.

11. A combination girdle and hernia truss, comprising a pair of similar, symmetrical front sections, a gusset having its side edges turned in stitched to the adjacent edges of said sections, eyelets carried by the gusset and the edges of said sections stitched thereto, a pair of side sections connected to the outer edges of said front sections by gussets having their side edges turned in and stitched to said front and side sections, lacing for each of said gussets forming sleeves of said gussets, and hernia pressure pads within the pair of sleeves formed by the gussets between said front and side sections.

12. A combination girdle and hernia truss, comprising a pair of similar, symmetrical front sections, a gusset having its side edges turned in stitched to the adjacent edges of said sections, eyelets carried by the gusset and the edges of said sections stitched thereto, a pair of side sections connected to the outer edges of said front sections by gussets having their side edges turned in and stitched to said front and side sections, lacing for each of said gussets forming sleeves of

said gussets, and hernia pressure pads within the pair of sleeves formed by the gussets between said front and side sections, said side sections having extensions forming leg bands, the outer ends of said leg bands being formed with lace openings, said outer ends being insertable within said pair of sleeves and attached thereto by the lacing for said sleeves.

13. A combination girdle and hernia truss, comprising a pair of similar, symmetrical front sections, a gusset having its side edges turned in 10, stitched to the adjacent edges of said sections, eyelets carried by the gusset and the edges of said sections stitched thereto, a pair of side sections connected to the outer edges of said front sections by gussets having their side edges turned

in and stitched to said front and side sections, lacing for each of said gussets forming sleeves of said gussets, and hernia pressure pads within the pair of sleeves formed by the gussets between 5 said front and side sections, said pads having lace openings to receive said lacing for said pair of gussets.

14. A combination girdle and truss having sleeves, truss pads within said sleeves and means to attach said pads to said sleeves in various adjusted positions, each pad comprising a bag and a compressible pad within said bag, said bag having two end tabs, one tab having a slot through which the other tab passes.

JULIUS ROSENZWEIG.
